[57] **CLAIM**

The ornamental design for a infrared receiver for controlling light fixtures, as shown and described.

DESCRIPTION

FIG. 1 is a top plan view of the infrared receiver for controlling light fixtures showing my new design;
FIG. 2 is a bottom plan view thereof;

FIG. 3 is an elevational view taken from the top of FIG. 1, the left and right sides having the same appearance except for the configuration of the top surface; and,
FIG. 4 is an elevational view taken from the bottom of FIG. 1.

FIG. 1

FIG. 2

FIG. 3

FIG. 4
